UNITED STATES PATENT OFFICE.

ALFRED COOK, OF LYNN, MASSACHUSETTS.

DESIGN FOR A SHOE.

SPECIFICATION forming part of Design No. 13,077, dated July 25, 1882.

Application filed May 10, 1882. Term of patent 14 years.

To all whom it may concern:

Be it known that I, ALFRED COOK, a citizen of the United States, residing at Lynn, in the county of Essex and State of Massachusetts, have invented and produced a new and original Design for Spring-Heel Shoes, of which the following is a specification, reference being had to the accompanying drawing, forming part thereof, which represents a spring-heel shoe, 10 showing the appearance of my design when finished.

Heretofore spring-heel shoes have been made without an ornamental stitch of any kind on the outer surface of the heel.

15 The object of my invention is to introduce a stitch on the outer surface of the heel, as shown in the stitch *b* in the drawing.

The single and leading feature of my design consists of the thread *b*, stitched on and around the outer surface of the heel from the point *d*, 20 to the junction of the heel and shank of the shoe, around the heel to a point corresponding with *d* on the opposite side of the shoe.

I claim—

The design for a spring-heel shoe, the same 25 consisting of the stitch *b*, sewed around the heel, as herein shown and described.

ALFRED COOK.
